Primary Examiner — Holly Baynham*Assistant Examiner* — Rhea Shields(74) *Attorney, Agent, or Firm* — Abbey A. Lopez; Amy I. Ahn-Roll**CLAIM**

The ornamental design for a carton, as shown and described.

DESCRIPTION

FIG. 1 is a perspective view of an embodiment of a carton;
FIG. 2 is a front view thereof;
FIG. 3 is a right view thereof;
FIG. 4 is a back view thereof;
FIG. 5 is a left view thereof;
FIG. 6 is a top view thereof; and,
FIG. 7 is a bottom view thereof.

In the drawings, the broken lines are for the purpose of illustrating environment only and form no part of the claimed design.
